UNITED STATES PATENT OFFICE

EDMUND T. ALLEN, OF SEATTLE, WASHINGTON, ASSIGNOR TO BOEING AIRPLANE COMPANY, OF SEATTLE, WASHINGTON

AVIATOR'S HELMET

Application filed March 19, 1930. Serial No. 436,977.

This invention relates to improvements in radio receiving and transmitting devices for use in aircraft operation, and more especially to an aviator's helmet embodying ear-phones for biaural use and a transmitting device adjustably and removably mounted with respect to the mouth of the operator.

The invention has for its principal object to associate with an aviator's helmet of any approved form, means whereby the aviator may efficiently transmit or receive conversational communication entirely through the helmet leaving his hands free for his customary duties.

Another object of the invention is to provide a means whereby the transmitting device may be adjusted into its operative or speaking position or swung entirely out of the way and locked against all except intentional movement.

These and other objects will appear as my invention is more fully hereinafter described in the following specification, illustrated in the accompanying drawings and finally pointed out in the accompanying claims.

In the drawings

Figure 1 is a front elevation of my improved form of helmet in use, showing the transmitting device in an operative position.

Figure 2 is a sectional side elevation of the helmet with parts removed, taken on the line "A"—"A" of Figure 1.

Figure 3 is a side elevation showing in dotted lines the range of adjustability.

Referring now more particularly to the drawings

Reference numeral 1 indicates any approved type of aviator's helmet which is provided with the usual extensions 2 and fastening means 3 for securing it to the head of the wearer. Apertures 4 are provided on each side of the helmet and are in open communication with pockets 5, within which are mounted ear-phones 6. Secured to the helmet at this same point is a pair of metallic plates 7 adapted to swingably support by means of bolts 8 a bail member 9, to which is mounted a transmitter 10. An electrical

circuit 11 embraces the transmitter and extends rearwardly to connect with any approved form of socket or the like. The ear-phones are likewise included in another electrical circuit (not shown in the drawings). 55

The bolts 8 are formed with knurled heads for convenience in tightening or loosening the bolts to adjust or lock the bail member in any position.

While I have shown a particular form of embodiment of my invention, I am aware that many minor changes therein will readily suggest themselves to others skilled in the art without departing from the spirit and scope of my invention. 60

Having thus described the invention, what I claim as new and desire to protect by Letters Patent is:—

1. In a helmet, in combination with means to support telephone receivers therein, a telephone transmitter and a support therefor pivotally supported to swing about, and otherwise non-adjustable relative to, pivot points on the receiver-supporting means. 70

2. In a helmet, in combination with means to support telephone receivers therein, a telephone transmitter and a support therefor pivotally supported to swing about, and otherwise non-adjustable relative to, pivot points on the receiver-supporting means, and means 80 for fixing said transmitter support in any one of a plurality of adjusted positions against all except intentional movement.

3. In a helmet, in combination with means to support telephone receivers therein, a telephone transmitter and a bail support therefor, the ends of which have circular holes, pivot bolts of a size to fill said holes, carried by said receiver supports thus providing a pivot for rotation of the bail thereabout, each 90 pivot bolt being provided with a knurled head for fixing said transmitter support in any one of a plurality of adjusted positions against all except intentional movement.

In testimony whereof I affix my signature. 95

EDMUND T. ALLEN.
